UNITED STATES PATENT OFFICE.

NICHOLAS R. MELVIN, OF MOUNT VERNON, NEW YORK.

REINFORCED-CONCRETE CRIB:

1,262,224.

Specification of Letters Patent.

Patented Apr. 9, 1918.

Application filed February 10, 1916. Serial No. 77,432.

To all whom it may concern:

Be it known that I, NICHOLAS R. MELVIN, a citizen of the United States, and resident of Mount Vernon, in the county of Westchester and State of New York, have invented a new and useful Improvement in Reinforced-Concrete Cribs, of which the following is a specification.

This invention relates to an improvement in reinforced concrete cribs for use in building structures forming a foundation upon which a superstructure may be raised, such as piers, bulkheads, seawalls, or breakwaters, etc., and has more particularly for its object to provide certain improvements in the crib and method of building the same.

A further object is to provide a crib having reinforced concrete members which are quickly and economically assembled and securely bound together.

A still further object is to provide a crib having reinforced concrete members which are adapted to be interlocked, presenting an approximately tight wall, whereby the interior filling will be prevented from sifting through the crib, especially when such filling as dirt, cinders, sand, etc., is used.

A still further object is to provide a crib having reinforced concrete ties and rangers adapted to be alternately assembled and secured at the points of intersection by fastening devices common to both.

A practical embodiment of my invention is represented in the accompanying drawings, in which—

Figure 1 represents a detail plan view of a portion of a crib, showing the position of a superstructure placed thereon in broken lines,

Fig. 2 represents a front elevation of the same,

Fig. 3 represents a transverse section taken from front to rear,

Fig. 4 represents a detail transverse section taken through the means of securing the members forming the crib together,

Fig. 5 represents a perspective view on a larger scale of one end of a tie,

Fig. 6 represents a detail front view of one end of a ranger,

Fig. 7 represents a transverse section taken in the plane of the line A—A of Fig. 6,

Fig. 8 is a detail plan view similar to Fig. 1 of a modified form of crib,

Fig. 9 represents a front elevation of the same, and

Fig. 10 represents a transverse section taken from front to rear.

The crib is composed of a series of reinforced concrete members placed in courses one above the other, each member of the course being arranged parallel to its adjacent member and each course laid at right angles to the adjacent course. The members forming the courses will, for the purpose of better identification, be called "ties" and "rangers". These concrete ties and rangers may consist of the material used, i. e., comprising cement, sand, gravel or broken stone. They may be molded in any well known and approved form and contain the usual longitudinal steel reinforcing rods.

The ties are denoted by 1 and are each provided with vertically tapered holes 2. The outer ends of the ties are formed with offset portions 3 having vertical walls oppositely arranged along their upper and lower faces. These ties are rectangular in cross section, but they may be made any desired shape and length to suit the requirements.

The rangers, denoted by 4, are provided along their upper and lower faces with ribs 5 having inclined walls extending longitudinally throughout the length of the ranger. These ribs 5 are cutaway as shown at 6, in Figs. 6 and 7, leaving the ranger at this point rectangular in cross section. The ranger has also formed therein, at this cutaway portion 6, vertically tapered holes 7, which, when the ties and rangers are assembled, will register with the holes 2 in the adjacent ties 1.

In the construction of a crib, the first course laid on the bottom should be ties, but this is not essential. These ties are preferably formed with an enlarged base throughout its length and wider than the regular tie, as shown in Figs. 1 and 2, the purpose of which is to prevent, so far as possible, the excessive settlement of the crib as the structure increases.

In Figs. 1 to 4 inclusive, these base ties 8

are formed with a thickened longitudinal central portion and tapered outwardly to the longitudinal edges and have screw threaded rods 9 secured at intervals throughout the 5 thickened portion, in any well known and approved manner, which rods extend upwardly to the desired height to which the crib is to be built. The rods 9 are also spaced apart a distance equal to the 10 distance between the holes 2 in the ties 1. The base ties 8, with their rods 9, are spaced apart a distance equal to the distance between the holes 7 in the rangers 4.

After the base ties 8, with their rods 9, 15 have been laid, the first course of rangers are laid at right angles to the ties, so that each ranger in the course will have one of the rods 9 of each of several base ties 8 passed through each hole 7 and the ranger 20 resting flat upon the tie. In the present form, the first rangers 10 are formed without the lower rib so that they may lie flat upon the base ties 8, thereby forming a firm seat upon which to build the following 25 courses.

The next course laid is a layer of ties 1 placed at right angles to the rangers 10, which ties are guided to their seats upon the rangers previously laid, by the rods 9 30 passing through the holes 2 in the ties. Each tie will, when in position, rest with its flat lower face in the cutaway portion 6 of the ranger, the offset portion 3 at each end of the tie being arranged so as to overlap 35 the ranger and prevent any outward movement of the ranger.

The next course laid will be a course of rangers laid at right angles to the ties, which rangers will be guided to their position upon 40 the ties previously laid, by the rods 9 passing through the holes 7 in the rangers, and so on until the height desired has been reached.

It will be seen that by cutting away the 45 portion of the longitudinal ribs 5 at the points of intersection of the ties, not only admits of a wider bearing surface for the ties upon the rangers, but it also allows the lower and upper ribs of each adjacent 50 ranger to approach each other and present an approximately tight face to the crib, which is advantageous for the filling of the crib.

After the last course of rangers has been 55 laid, or at any time during the progress of the work, ferrules 11 may be placed on the projecting upper threaded portion of the rods 9 and by means of nuts and washers 12 the ties and rangers may be forced downwardly to their proper position and securely bound together.

In order to give the upper face of the crib an uninterrupted surface, as well as protect the projecting ends of the ties, the upper 60 courses of rangers along the face may be

made wider, as shown at 13 in Figs. 1, 2 and 3, thereby furnishing an approximately smooth face.

I also find it advantageous in laying the courses of rangers to break the joints of the 70 abutting rangers in each course, thus stiffening the structure and preventing any lateral movement.

In the form shown in Figs. 8 to 10 inclusive, I have shown a crib built of ties 75 14 and rangers 15, both of which are rectangular in cross section. The base tie 16 may be formed wider, but the rangers are all formed alike.

It will be understood that when the crib is 80 built the pockets or cellular openings 17 will be filled with stone rip rap of size commonly known as "one man" stone, upon which the superstructure 18 of the reinforced concrete may be placed, as shown 85 in broken lines in the several figures.

In the form shown in Figs. 1 to 4 inclusive, the pockets may, for the purpose of economy, be filled with dirt, cinders, or sand 90 instead of stone.

The advantage of building a crib with these premolded concrete ties and rangers is made clear from a consideration of the fact that the ties and rangers of this invention are manufactured as separate individual units of such shape, size and length that they can be conveniently handled, and set in the place the crib is to permanently occupy. Furthermore, the life of the crib is practically unlimited, as it is free from decay 100 either from natural causes above the water, or from the action of marine borers, etc., below the water.

It is evident that slight changes may be resorted to in the form, construction and arrangement of the several parts without departing from the spirit and scope of my invention; hence I do not wish to limit myself strictly to the structures herein shown and described, except as they may be particularly set forth in the claims.

What I claim is:—

1. A crib comprising a series of reinforced concrete base ties, each having an enlarged base and upwardly extended rods secured 115 therein, a series of reinforced concrete ties having vertically tapered holes arranged to be slid on said rods, said ties being provided with bodies rectangular in cross section and portions offset therefrom at their ends, a 120 series of reinforced concrete rangers having vertically tapered holes arranged to be slid on the rods in alternate courses with the ties, said offset portions being arranged to overlap the outermost rangers above and 125 below each of the ties and means on said rods for securing the ties and rangers together.

2. A crib comprising a series of reinforced concrete base ties, each having an enlarged 130

base and upwardly extended rods secured therein, a series of reinforced concrete ties having vertically tapered holes arranged to be slid on said rods, said ties being provided 5 with bodies rectangular in cross section and portions offset therefrom at their ends, a series of reinforced concrete rangers having vertically tapered holes arranged to be slid on the rods in alternate courses, with the 10 ties and provided with longitudinal ribs having inclined walls extending the length of the rangers between the ties, said offset portions being arranged to overlap the outermost rangers above and below each of the ties, and means on said rods for securing 15 the ties and rangers together.

3. A reinforced concrete base tie for use in cribs having a thickened longitudinal central portion and tapered outwardly to the longitudinal edges and vertical rods 20 secured at intervals throughout the thickened portion.

In testimony, that I claim the foregoing as my invention, I have signed my name this first day of February, 1916.

NICHOLAS R. MELVIN.
